UNITED STATES PATENT OFFICE.

MURT L. O'NEIL, OF FORT SHAW, MONTANA, ASSIGNOR OF ONE-HALF TO ROBERT G. DAY, OF GREAT FALLS, MONTANA, AND ONE-HALF TO MARTHA J. O'NEIL, OF SUN RIVER, MONTANA.

PROCESS OF ROAD BUILDING.

Application filed March 14, 1922. Serial No. 543,748.

To all whom it may concern:

Be it known that I, MURT L. O'NEIL, a citizen of the United States, residing at Fort Shaw, in the county of Cascade and State 5 of Montana, have invented certain new and useful Improvements in Processes of Road Building, of which the following is a full, clear, and exact description.

My invention relates to processes for 10 building roads, more especially gravel and sand roads, and one of its objects is to agitate the gravel so as to work the larger pebbles or stones to a position where they may thereafter be readily worked to the bottom of the road.

Another object of the invention is to agitate the surface of the remodeled road so as to extract any large stones near the surface and thereafter work the same toward the outside edge of the crown of the 20 road.

Other objects and advantages of the invention will be apparent from the following description when taken in connection with 25 the accompanying drawing, in which:

Figure 1 is a partial section through a sub-grade, showing the gravel road in elevation as formed by processes now in use.

Figure 2 is a similar view, showing one 30 of the steps of my process, and

Figure 3 is a similar view, showing the various positions of the different sizes of gravel in the completed road.

In building gravel roads the ideal formation is to have the large size stones along the bottom and at the edges of the road, then a layer of the next smaller size gravel, and so on to the surface of the road, which should be composed of the finest gravel only.

To this end it has been the usual practice to 40 screen the gravel into various grades and then place it in layers on the road, but quite often after using this expensive process the ideal condition is not attained, for the reason that the process of spreading and dragging necessary to secure a true and uniform surface tends to work the fine material to the bottom, leaving the coarse particles on top, thus again producing a condition 50 exactly opposed to the ideal. By the use of the hereinafter described process the expensive process of screening the gravel can be dispensed with and at the same time a

road is built having substantially the ideal formation heretofore referred to. 55

Where my process is to be used in connection with rebuilding a gravel road which has become hardened and compacted by much usage, etc., the aggregates are first loosened by means of a scarifier in a manner well understood by those skilled in the art of road building. After the gravel is loosened in this manner a blade grader is drawn therethrough by a caterpillar or other tractor. In this step of the process the blade 60 is set at an acute angle with the direction of travel with two or three feet of the forward end of the blade partly buried in the gravel, the remainder of the blade being useful in pushing the gravel forward and to one side. 65 One, two or more round trips are made with the blade grader, depending on the width of the gravel surface and the size and, percentage of the larger size stones. By this method the gravel is thoroughly mixed and 70 is formed into one or two ridges paralleling the center line of the road. During this process of building up the ridge or ridges the larger size stones tend to run ahead of the smaller aggregates 75 and, therefore, take 80 positions at the base of the ridges, as indicated by the numerals 1, 2 and 3 in Figures 2 and 3. Of course, the more the material is worked in this manner, the greater will be the degree of separation between the various 85 grades of the material.

After the ridges are formed as shown in Figure 2 it is preferable, though not always necessary, to agitate the surface of the ridges by drawing a scarifier, rake or other 90 toothed apparatus along the top of the ridges, thereby further aiding in bringing the larger size stones to the surface.

The gravel being placed in the condition just described, the blade grader is again 95 brought into use. The grader is drawn a number of times along the ridges, the blade being set so as to gradually spread the gravel back over the sub-grade. Here again the larger size stones traveling faster 100 than the smaller ones reach the sub-grade first and thereby form the base of the gravel road, the next smaller size stones covering the former, and so on, the fine gravel forming the upper surface of the road.

After the ridges have been worked back 105

in the manner just described, it is, of course, possible that some large stones may remain near the surface, and it is, therefore, advisable, though not always necessary, to 5 draw a scarifier or other toothed apparatus over the surface of the road, thereby agitating the gravel to the depth of one or two inches, which will bring any of the remaining large stones to the surface of the 10 road. The blade grader may then be drawn over the surface, moving the larger stones to the edge and base of the road. In these last trips of the blade grader any soft spots remaining are found by the weight of the 15 tractor and are filled in by the material carried by the blade of the grader. It may be here stated that during the respreading operation a surplus of crown is carried on the surface which is gradually diminished 20 as the surface approaches the proper cross section, the purpose being to reserve enough of the fine material to cover the large size stones toward the edge of the road.

While the foregoing process has been described in connection with rebuilding roads, 25 it is, of course, to be understood that the same may be as well used in new road construction and with equally beneficial results. In either case a binder, such as clay or the 30 like, may be used if necessary; this is done by spreading the clay over the gravel before the process begins.

In Figure 1 of the drawing the numerals 35 5 and 6 indicate hard and soft spots, respectively, which necessarily result from an indiscriminate mixing of the various sizes of stones forming the gravel roadbed.

In accordance with the patent statutes, I have described what I now believe to be 40 the best embodiment of the invention, but I do not wish to be understood thereby as limiting myself or the scope of the invention, as many changes and modifications may be made without departing from the 45 spirit of the invention; all such I aim to include in the scope of the appended claims.

What I claim as new and desire to secure by Letters Patent is:

1. A process of building gravel roads, 50 which includes blading the material into one or more ridges, whereby a portion of the larger stones descend to the bottom of the ridge or ridges, and then blading the material of the ridges so as to respread the gravel 55 over the road bed, thereby causing practically all of the larger stones to descend to the road bed.

2. A process of building gravel roads, which includes adding a binding material to the gravel, mixing the gravel and binding material by blading the same into one or more ridges, whereby a portion of the larger stones descend to the bottom of the ridge or ridges, and then blading the material of the ridges so as to respread it over the road bed, 60 thereby causing practically all of the larger stones to descend to the road bed.

3. A process of building roads, including the reserving of a portion of the fine material for the surface of the road by means 70 of blading the material into one or more ridges so as to cause a portion of the larger stones to descend to the base of the ridge or ridges, and then gradually blading the material to proper cross-section, whereby the 75 larger stones first reach the sub-grade, leaving a large portion of the fine material for the surface.

4. A process of building gravel roads, which includes working the gravel into a 80 longitudinal ridge, agitating the surface of the ridge, and gradually respreading the gravel over the roadbed.

5. A process of building gravel roads or the like, which includes working the gravel 85 into a ridge, respreading the gravel over the roadbed to form a crown, agitating the surface of the crown, and moving the pebbles thus brought to the surface to the edge of the crown.

6. A process of building gravel roads, which includes blading the gravel into one or more ridges, agitating the surface of the ridges, gradually blading the ridges to respread the gravel over the sub-grade of the 90 road to form a crown, and agitating the surface of the crown.

7. A process of building gravel roads, which includes working the gravel into one or more ridges, gradually blading the ridges 100 to respread the gravel over the sub-grade of the road to form a crown, agitating the surface of the crown, and removing the stones brought to the surface by such agitation.

8. A process of rebuilding gravel roads, which includes scarifying the surface of the road, blading the loosened gravel into one or more ridges, gradually respreading the gravel over the sub-grade of the road to 110 form a crown, and agitating the surface of the crown.

MURT L. O'NEIL.
